UNITED STATES PATENT OFFICE.

DANIEL RAYMOND McNEAL, OF PALMYRA, NEW JERSEY, ASSIGNOR TO ANDALE ENGINEERING COMPANY, A CORPORATION OF PENNSYLVANIA.

STRAINER.

Application filed February 13, 1924. Serial No. 692,488.

This invention relates to strainers and is particularly useful in that type of strainer known as a duplex strainer in which the fluid to be strained may be passed through 5 either strainer when it is desired to remove the other strainer for cleaning purposes.

One of the primary objects of my invention is to produce a simple, compact and sturdy construction, comparatively inexpensive to manufacture and occupying a 10 minimum of space.

Another object of the invention is to provide a construction of strainer such that the machining operations may be greatly 15 simplified and the cost thus cheapened.

A further object has to do with the provision of an arrangement of parts such that the position of the valve or valves may be determined from the exterior at a glance.

20 Still another object of the invention is to provide an arrangement of the valve such that the parts may be interchanged or reversed making it possible to install the strainer in what would otherwise be inaccessible locations.

My invention further contemplates an arrangement and disposition of parts such that the body or casing forming the valve chambers and the strainer chambers may be cast 30 in one piece.

The foregoing, together with such other objects as may hereinafter appear, or are incident to my invention, I obtain by means of a construction, the preferred embodiments 35 of which are illustrated in the accompanying drawings wherein

Fig. 1 is a section thru the strainer taken on the line 1—1 of Fig. 2;

Fig. 2 is a section taken on the line 2—2 40 of Fig. 1;

Fig. 3 is a section taken on the line 3—3 of Fig. 1;

Fig. 4 is a section illustrating a detail 45 of the construction.

Referring now to Fig. 1 the reference character "A" designates the casing or body of the strainer, such casing having opposed, aligned, flanged inlet and outlet portions 7 and 8 respectively, for attachment 50 in the line. The casing has two cylindrical portions 9 and 10, a central division wall 11, and two spaced division walls 12 and 13, providing two valve chambers, B and C, and two strainer chambers D and E. The

cylindrical portions 9 and 10 merge with 55 the walls 12 and 13 at the middle portion of the latter, and the wall 11 merges with the walls 12 and 13 at about their middle portion.

Each wall 12 and 13 has two port openings 15 and 16 and 17 and 18. The cylindrical portion 10 has an inlet port 19 establishing communication between one end of the valve chamber B and the interior of such cylindrical or strainer chamber; and the cylindrical portion 9 has a similar port opening 20 establishing communication between the opposite end of the valve chamber B and the interior of such cylindrical or strainer chamber. Each of the cylindrical portions 9 and 10 is provided with an outlet port, 21 and 22, respectively leading into opposite ends of the valve chamber C.

It will be observed from the foregoing that the strainer chambers are between the 75 valve chambers and extend at right angles to the median plane of the device indicated by the line 1—1 of Fig. 2. Heretofore in devices of this character it has been customary to arrange the strainer chambers on 80 opposite sides of the median plane and parallel thereto, i. e. there was a strainer chamber on each side of the device extending longitudinally thereof and communicating with each valve chamber on each side. By 85 the present arrangement a much more compact, simple and effective construction is secured having the advantage, among other things, of making it possible to cast the entire body in one piece.

The portion of the casing forming the outer wall of the valve chambers is rounded, as the result of which there is no flat un-stayed surface, which is an additional feature of advantage particularly where the 90 pressures employed are high, as maximum strength is secured with a minimum weight of metal.

The valves 23 and 24 are double faced, the former being adapted to seat either on the valve seat 12^a or the valve seat 13^a, while the latter is adapted to seat either on the valve seat 16^a or 18^a.

The valves are carried on shouldered 100 valve stems 25, and are clamped between the shoulders and the nuts 26. The end 25^a of each valve stem is slidably received in the rear bearing 27, for the reception of

which the casing is provided with the apertured seat portion 28, the surfaces 29 and 30 of which are machined.

The opposite end 25^b of each valve stem is slidable in the gland bearing 31, for the reception of which the casing is provided with the apertured seat portion 32 having machined surfaces 33 and 34. The bearings 27 and 31 are secured to the casing by 10 screws.

The ends 25^b of the valve stem extend through the gland bearing well to the exterior of the strainer casing or body and are threaded.

15 The valve stems are moved longitudinally by means of the nut 35 carried in the yoke 36 which in turn is carried by a pair of studs 37. A hand wheel 38 is fitted to a square portion of the nut 35 and held in place by means of the nut 39 which also serves to position the nut 35 with respect to the fixed yoke 36, so that while the nut 35 is free to be rotated, it cannot be displaced longitudinally, as a result of which 20 when it is turned, it imparts longitudinal movement to the valve stem.

By having the valve stems project to the exterior and by having the valves fixed with respect to the valve stems so that movement is imparted thereto by longitudinal movement of the valve stems, the position of the valves is immediately indicated by the position of the projecting ends of the valve stem and one is immediately apprised not 25 only as to the position of the valve but also whether or not there is any obstruction tending to prevent the valve from being properly seated.

The bearings 27 and 31 are interchangeable, so that it is possible to insert the valve stem either end to. By virtue of this arrangement, if the device is not capable of being installed with the ends of the valve stems projecting from one side, they may 45 be reversed so as to project from the other side. This is a feature of considerable importance for very frequently the strainers have to be installed in relatively inaccessible places.

The surfaces 29, 30, the valve seats, and the 50 surfaces 33 and 34 may all be machined in a single operation. The valves 23 and 24 are introduced or removed through the openings 40 covered by the cover plates 41.

The strainers are slidably supported in 55 the strainer chambers in the manner indicated in Fig. 1 and are introduced and removed through the open end 42 of the strainer chambers, such open end being closed by the hinged, arcuate lid or cover 60 43 releasably clamped in position by means of the clamping device 44, the construction and operation of which will be readily understood.

By reference to Fig. 4, it will be seen 65 that the studs 37 are surrounded by sleeves 37^a, such sleeves serving to space the yoke 36 with reference to the strainer body.

I claim:

1. In a strainer, a strainer body having a 70 valve chamber, a valve, a valve stem carrying the valve intermediate the ends of the stem, a pair of bearing members for the ends of the stem interchangeably carried on the body whereby the stem may be reversed 75 end for end, and means for manually shifting said valve into one position or another.

2. In a strainer, a strainer body having a valve chamber, a valve, a valve stem carrying the valve intermediate the ends of the 80 stem and a pair of bearing members for the ends of the stem interchangeably carried on the body whereby the stem may be reversed end for end, an end of the stem projecting 85 exteriorly of the body.

3. In a duplex strainer, a body having two valve chambers, each having two spaced valve seats, a double faced valve for each chamber, means for moving the valves, and a pair of cylindrical strainers located between said means for moving the valves, said strainers being arranged with their longitudinal axes lying in a common plane separating said valve chambers.

In testimony whereof, I have hereunto 95 signed my name.

D. RAYMOND McNEAL.
